TANK FOR STEAM IRONS

Wilfred E. Ellinwood, St. Louis, and Henry V. Ekstedt, Overland, Mo.

Application May 31, 1946, Serial No. 673,344

7 Claims. (Cl. 38—77)

1

This invention relates in general to certain new and useful improvements in tanks for steam irons.

It is a primary object of the present invention to provide a steam iron tank which is uniquely constructed to minimize splashing of water as the iron is being moved to and fro during use.

It is also an object of the present invention to provide a tank for a steam iron so constructed that globules of water condensate and liquid spray cannot become entrained with, and pass outwardly from, the discharge tube with the steam generated in the tank.

It is an additional object of the present invention to provide a steam iron tank which may be conveniently and economically stamped from sheet metal and welded together in a strong, but lightweight, and inexpensive structure.

It is also an object of the present invention to provide a non-splashing steam iron tank which will not readily become caked up and fouled with deposited incrustations of calciferous matter due to the use of water having appreciable hardness.

It is an additional object of the present invention to provide a steam iron tank which is externally insulated so that the iron itself is comparatively cool on its external side faces above the sole plate and is, therefore, much safer and much more comfortable for the user.

And with the above and other objects in view, our invention resides in the novel features of form, construction, arrangement, and combination of parts presently described and pointed out in the claims.

In the accompanying drawings—

Figure 1 is a longitudinal sectional view of a steam iron constructed in accordance with and embodying the present invention;

Figure 2 is a longitudinal sectional view of a steam iron tank constructed in accordance with and embodying the present invention;

Figures 3 and 4 are transverse sectional views taken, respectively, along lines 3—3 and 4—4 of Figure 2;

Figures 5, 6, and 7 are top plan views of the several partitions incorporated in and forming a part of the steam iron tank of the present invention;

Figure 8 is a longitudinal sectional view of a modified form of steam iron tank constructed in accordance with and embodying the present invention;

Figure 9 is a transverse sectional view taken along line 9—9 of Figure 8;

Figure 10 is a longitudinal sectional view of a

2

further modified form of steam iron tank constructed in accordance with and embodying the present invention; and

Figure 11 is a transverse sectional view taken along line 11—11 of Figure 10.

Referring now in more detail and by reference characters to the drawings, which illustrate practical embodiments of our invention, A designates a steam iron of a type more fully and completely disclosed in our copending application, Serial No. 644,358, filed January 30, 1946, and includes a handle 1, an outer shell 2, a heating element 3, a sole plate 4, a steam eduction fitting 5, and a thermostatic control element 6. Disposed within the outer shell 2 is a tank T comprising a deep-drawn body section 7 flanged slightly outwardly around its peripheral margin, as at 8, and welded to a transversely extending closure member or bottom plate 9, which is provided in the region of its center with an upwardly pressed recess 10 for enclosing the thermostatic control element 6. Rearwardly of the recess 10, the bottom is provided with a second recess 11 aligned with a similar inwardly pressed recess 12 formed in the top wall 13 of the body section 7. The recesses 11, 12, are furthermore provided with aligned apertures 14, 15, having inwardly extending peripheral flanges 17, 18, for embracingly receiving a connecting tube 19 which projects at its ends a short distance therethrough and is brazed in place. It should be noted in this connection that the outward extension of the ends of the tube 19 and the flanges 17, 18, uniquely facilitate the brazing operation and insure tight permanent joints at these points.

Similarly, the recess 10 is provided with an aperture in vertical alignment with a shallow apertured recess 20 for accommodating a passage tube 21. Also brazed, welded, or otherwise secured upon the inner face of the bottom wall 9 is a tapped boss 22 adapted for threadedly receiving the steam eduction fitting 5 and being provided with an upwardly extending co-axial steam eduction tube 23 opening at its upper end just beneath the top wall of the body section 7 and communicating at its lower end, through a passage 24 formed in the boss 22, with the fitting 5.

Disposed within the interior of the tank T in spaced parallel relation to each other, and to the bottom wall 9, are two intermediate partitions 25, 26, preferably contoured to fit snugly against the interior face of the body section 7, being suitably bored to pass the tubes 19, 21, and 23. Riveted upon the under face of the partition 25, and extending angularly downwardly therefrom, are

3
two transverse support members 27, 28, provided at their lower extremities with foot-forming flanges 29, 30, for resting abuttingly upon the upper face of the bottom wall 9. Along their lower transverse margins, the support members 27, 28, are cut away, as at 31, and along their vertical margins terminate a short distance inwardly from the side walls of the body section 7 to provide areas of intercommunication permitting flow of water lengthwise through the tank T.

Similarly riveted upon the under face of the partition 26 is a pair of support members 32, 33, similar in shape and construction to the support members 27, 28. The partition 26, furthermore, is provided with an upwardly and rearwardly bent stabilizing plate 34 flanged over at its upper margin, as at 35, for abutment against the inner face of the top of the body section 7.

Also riveted upon the upper face of the partition 26 in its forward area, and in the region of its center line, is a U-shaped support member 36 having a horizontal bight section 37 provided with a partition plate 38 having arcuate lateral margins adapted to conform to and fit against adjacent portions of the side walls of the top section 7, and further being provided with forward and rearwardly presented straight margins which are spaced from opposed portions of the side walls of the top section 7. The bight member 37 and its associated partition plate 38 are suitably bored to pass the tubes 21, 23.

The partition plates 25, 26, are provided with a plurality of apertures 39, as shown in Figures 6 and 7, for permitting the rapid flow of steam upwardly through the tank T. The partition plate 38, however, is solid and, similarly, the support members 27, 28, 32, 33, and 35 are solid except for the clearance recesses 31, thereby cooperating to prevent the to and fro splashing of water as the iron A is moved forwardly and backwardly during actual use. Furthermore, when the iron A is tilted backwardly upon its heel, the water in the tank will flow into the heel portion thereof, and when the iron A is returned to normal ironing position, the partitions 25, 26, the partition plate 38, and the support members 27, 28, 32, 33, and 35 will operate to force the water downwardly against the bottom wall 9 without splashing and will prevent particles of water or liquid spray from splashing up against the upper wall of the top section 7 and accidentally entering the upper end of the steam eduction tube 23 or otherwise becoming entrained in the steam flowing outwardly therethrough.

While stabilizing the liquid contents of the tank T, the partition members 25, 26, are provided with a sufficient number of apertures to allow for the rapid and substantially unimpeded passage of steam upwardly to the upper end of the steam eduction tube 23 and will not become clogged due to the accumulation of calciferous scale and similar deposits.

If desired, a modified form of steam iron tank T' may be provided, as shown in Figures 8 and 9, being substantially similar in all respects except that the partition 26' is provided in its central region with an auxiliary baffle member 40 extending transversely thereacross and projecting downwardly and rearwardly to a point approximately midway between the partition 26' and the partition 25' directly therebeneath. Also riveted to the under face of the partition 26' is a downwardly and forwardly extending auxiliary baffle member 41 which projects beneath and is spaced a short distance downwardly from the

5 lower transverse margin of the baffle 40 and projects a short distance therebeyond, being flanged upwardly, as at 42, to provide a somewhat convoluted passageway 43. The auxiliary baffles 40, 41, assist in controlling the shifting movement of the water in the tank and in the prevention of splashing and liquid entrainment. More specifically, it is believed that these auxiliary baffles 40, 41 create a sort of vacuum-like flushing action, 10 as a result of the to and fro movement of water during actual ironing operations, similar in nature to the vacuum condition created in the vortex of a whirlpool, which flushing action functions to facilitate the withdrawal or downward flow of any liquid which may accidentally become 15 lodged on the upper side of the horizontal partition 26'.

If desired, a further modified form of steam iron tank T'' may be provided, as shown in Figures 10 and 11, being substantially similar in form to the previously described steam iron tanks T and T', except that three spaced parallel partitions 44, 45, and 46 are provided and are spaced from each other by downwardly inclined support 20 members 47, 47', 48, 48', 49, and 49', the latter being formed of somewhat springy material and being bent at such an angle that, when the partitions 44, 45, and 46 are placed within the tank T'' during assembly, it is necessary to flex the 25 support members, 47, 47', 48, 48', 49 and 49' slightly and place them under so-called spring tension in installing the bottom member 9. By this means, the partitions are held tightly in place under spring-like pressure when the tank 30 T'' is finally assembled.

It should be understood that changes and modifications in the form, construction, arrangement, and combination of the several parts of the steam iron tank may be made and substituted for 35 those herein shown and described without departing from the nature and principle of our invention.

Having thus described our invention, what we 40 claim and desire to secure by Letters Patent is:

1. A self-contained interior steam tank for a steam iron comprising an entirely closed hollow sheet metal shell having a substantially flat bottom, said bottom having a recess therein adapted to receive a thermostatic control element, a thermostatic control shaft receiving tube extending upwardly from said recess and opening through the top of said shell, a bolt receiving tube opening through the top and bottom of said shell, and a steam eduction tube communicating with the interior of said shell below the top thereof and opening through the bottom of said shell.

2. A self-contained interior steam tank for a steam iron comprising an entirely closed hollow

60 sheet metal shell having a substantially flat bottom, a plurality of perforated partitions located in said shell and permanently connected in spaced substantially parallel relation to each other and to said bottom wall to form a pre-65 assembled partition unit, said bottom having a recess therein adapted to receive a thermostatic control element, a thermostatic control shaft receiving tube extending upwardly from said recess and through said partitions and opening through the top of said shell, a bolt receiving tube opening through the top and bottom of said shell and extending through said partitions, and a steam eduction tube extending through 70 said partitions and communicating with the in-75

terior of said shell below the top thereof and opening through the bottom of said shell.

3. The combination set forth in claim 2 where-
in said recess is located substantially midway
of the length of said shell, said bolt receiving
tube is located rearwardly of said recess and said
steam eduction tube is located in front thereof.

4. The combination set forth in claim 2 where-
in an additional partition plate is located in
said shell above the topmost perforated parti-
tion in spaced relation thereto and to the
top sides and ends of said shell and said control
shaft receiving and steam eduction tubes extend
through said additional partition plate.

5. A self-contained steam iron tank comprising
an entirely closed hollow shell having a sub-
stantially flat bottom, a plurality of perforated
partitions located in said shell and disposed in
spaced substantially parallel relation to each
other and to said bottom wall, said bottom having
a recess therein adapted to receive a thermo-
static control element, a tube extending up-
wardly from said recess and through said parti-
tions and opening through the top of said
shell, a second tube opening through the top and
bottom of said shell and extending through
said partitions, and a third tube extending
through said partitions and communicating
with the interior of said shell adjacent to the
top thereof and opening through the bottom
of said shell, and two transverse baffle plates
inclining downwardly toward each other from
the topmost partition with their lower marginal
portions disposed in closely spaced overlapped
relation to provide a passageway therebetween.

6. A self-contained steam iron tank comprising
an entirely closed hollow shell having a sub-
stantially flat bottom, a plurality of perforated
partitions located in said shell and disposed in
spaced substantially parallel relation to each
other and to said bottom wall, said bottom having
a recess therein adapted to receive a ther-
mostatic control element, a tube extending up-
wardly from said recess and through said parti-
tions and opening through the top of said shell,
a second tube opening through the top and bot-
tom of said shell and extending through said
partitions, and a third tube extending through
said partitions and communicating with the in-

terior of said shell adjacent to the top thereof
and opening through the bottom of said shell,
said shell having downwardly diverging sides,
and resilient members associated with said parti-
tions for holding them apart from one another
and from the top and bottom of said shell and
for seating them against the diverging sides
thereof.

7. A self-contained steam iron tank comprising
an entirely closed hollow shell having a sub-
stantially flat bottom, a plurality of perforated
partitions located in said shell and disposed in
spaced substantially parallel relation to each
other and to said bottom wall, said bottom having
a recess therein adapted to receive a thermo-
static control element, a tube extending up-
wardly from said recess and through said parti-
tions and opening through the top of said shell,
a second tube opening through the top and bot-
tom of said shell and extending through said
partitions, and a third tube extending through
said partitions and communicating with the in-
terior of said shell adjacent to the top thereof
and opening through the bottom of said shell,
and members permanently secured to said per-
forated partitions for holding them apart from
one another and from the top and bottom of
said shell.
